Caton & Rives.

Registering Arms for Printing Press.

No

Patented Mar. 11. 1835.

Michael Galen and John C. Price, of Washington D.
Letters Patent

The独创的 referred to in the above Letters Patent and making part
of the same containing a description in the words of the said Michael Galen
and John C. Price, inventors of this improvement, in
printing on a Double Printing Press.

To all to whom these presents shall come. Be it known that
the Michael Galen and John C. Price, of the City of Washington
in the District of Columbia have invented a new and useful
improvement in printing on a Double Printing Press, whereby
a printed page may be made perfect on it, -
that is, the printing on the side of the sheet first worked off
completely covered when it is backed or printed on the other
side, or in other words the two printed pages on each leaf
of a book made exactly opposite to each other. A full de-
scription of the improvement made by us follows.

1st. Name two points on the cylinder (or cylinders if it be
a double printing press) so near to it that a sheet will not pass
between them and the cylinder when putting it on and at such
places that the fore and corners of the sheet when rightly laid on
will rest against these points. The points are to be placed to the right
of the registering apparatus so as in use to hold up with one hand
just at the moment the fingers of the press take hold on the sheet and
keep them raised until the sheet passes from under them; and the
instant that is done, drop to the printing post ready, that is to say
the cylinder that a sheet cannot pass between it and the points.
If the paper is off the same (as by putting away that against
the points and the quite at the sides all the margin of the
printed sheet will be the same (as by which is the principal
object for using them). In the drawing of perspective view of
cylinders to separate the cylinder from the arms of the press by
which they are guided is the shaft that carries the press. H. G. P.

of leather upon which the points rest. At the end of the board below the points of the prints are placed 2. Make two points, and in the head of each make a ^{notch} ~~notch~~ as a base and about the ~~size~~ ^{size} of
long ~~prints~~ ^{prints} or ~~size~~ ^{size} these, and one of the ends of the leather
upon which these should be just as high as the type sticks up in it, so
at such places that they will make an impression upon the
printed sheet about an inch from each edge of it. In working
off the first side these points will make impressions in every line
that may be seen distinctly when the paper is turned to work off the
second side. The cylinders of a double Napier Peep fall a little
when passing over the cross bar in working a form on it, therefore the
heads of the points should not be quite so high as the type, because
if they are they will frequently break a hole through the paper which
should not be done. The points should be so regulated that their
heads will make about the same impression as are made by the
type. See drawing of . . . place and size of the points. To repre-
sent the cross bar of the cheer and a. the doors.

3. Place on the inclined board upon which the sheet is laid to
be taken off by the fingers of the press. The movable points just the
distance apart as the spaces in the cheer are. These points should
rise about one fourth of an inch above the board. In working off
the first side put the centre of the o. made on the paper by the
points on the cheer in working off the first side, equally over them
prints, and more than sufficient may be employed until the
form will make register on the sheet when it is taken off by
the fingers of the press. It will require a boy on each side of the
sheet to lay on the sheet when working off the second side.

This is what makes prints really suitable to lay on 25,000
a minute, which are as many as can be worked off within that
time by a single cylinder. In working off the second side the points
that have not yet been used for the bottom may be used instead
of those that have, so that the points that are used will not be used
again. They should be struck through the sheet in the centre of the o. and

by the heads of the Sticks when printing the first side. We think the points that rise and fall are preferable to those which do not, because a glance at the printed Stock will show the importance of the Dots whether the Charts have been laid on correctly. If the Dots should not be made holes in the Charts through the centre of the o. then it is certain that the Charts have not been laid on correctly; but if they have been struck through the centre of the o. and the form and are made regular it proves the Charts have not been laid on as they should be and that the points should be made the crossing delineated "Perspective view of the cylinder." It separates the inclined board upon which the Charts are laid and the points. We are forced to think that the several descriptions of incisions mentioned in this Specification are improvements at least of twelve some of them may not properly be styled, original inventions. First as to the advantages claimed by using points on the cylinder. They enable the Printer when the paper is all the same size to make all the margins the same size, which is very difficult when it is necessary to bind the parts, and especially when the edges are not to be cut. Besides it is more easy to lay the Stock when they are used; and they prevent the Charts being laid too far apart, which spoils them when the margins are small. Whether one of these points alone good results may be made on newspaper which is important when they are to be bound. Some of the forms on the chart they make an uneven mark on the Chart when printing the first side to print by printing the second side. This is done too without the least detection or trouble; as a consequence of a person to a cylinder to lay the Charts; when as all the other modes of marking, register or a Mapa Proportion too present a cylinder to lay on the Charts when laying them on to print the first side. The cause appears often being forward to print the Charts when laying them on to print the first side; and to print through the holes made in the Charts on printing the first side, when printing the second side. There are two objections

In these months we much more concerned to revolutionize the process in the chase, First the "points" being unmovable are often ruined by accident while "perfect register" being made on these sheets that are printed while the points are so moved, Second The sheet frequently slips after being fast before it gets on the form, which also causes the register being made, if indeed it does not spoil the sheet entirely. When printed in the chase we use they invariably make marks on the sheet on printing the first side of each sheet that perfect register will be made in printing the second side of the sheet is correctly pointed even if it has slipped on printing the first side either before or after the fingers of the press took hold of it. Third the points on the inclined board. As these are recommended now and circulated by us we bear it necessary to say anything about them here, except to say that with these improvements perfect register may be made. The above Specification of the improvements which we have made in printing on a new Press is so detailed as full that it will enable any "Master Skilled in the art or Science of which it is a branch or with which it is most nearly connected, to make compound and use the same, which the law requires.

We have used the screws in the chase about a year and the points in front of the inclined board, five or six months and we claim them to be useful and necessary that we could not forego the use of them, for one thousand Dollars a year if we had as much book work as we could print on a double new Press. We beg leave to file ^{English} the original Globe dated the 19 January 1835, which was printed on a double new Press with our improvements attached to it. It will show the impressions which the screws make on the paper in printing the first side, also the point holes made through the paper in printing the second side. The Register is not perfect on this sheet, which is owing as will be seen to not printing through the centre of the, made by the screws. We think it proper to say in conclusion that we consider the screws in the chase the greatest improvement we have made and the are most easy to get and are made by those who might wish to use it without paying for it, and therefore we claim it necessary to do

some of the modes by which certain might be attempted. If you find
part of the team being right locked up in the stable near a
crophouse or they might be fastened or near the gate or all sticks
is locked up in some other part of the farm so as to answer the purpose
of the persons though they would not do so well. Believing that no
person before us has ever attempted to make register by marking a mark
upon the shaft with any thing connected with the shaft we claim
the exclusive right of doing so; and shall consider each and every
attempt of the kind by any other person or persons without our per-
mission as an infringement upon our rights. — In testifying that the
above is a true Specification of our said improvement we have here-
unto subscribed our names the 4th day of February 1835.
